UNITED STATES PATENT OFFICE.

JOHN T. KELLY, OF NEW YORK, N. Y., ASSIGNOR OF ONE-HALF TO GEORGE M. JONES, OF PITTSBURG, PENNSYLVANIA.

DESIGN FOR A COUPLING MEMBER FOR RADIATOR-VALVES.

SPECIFICATION forming part of Design No. 33,258, dated September 25, 1900.

Application filed March 28, 1900. Serial No. 10,558. Term of patent 14 years.

To all whom it may concern:

Be it known that I, JOHN T. KELLY, a resident of New York, (Brooklyn,) in the county of Kings and State of New York, have invented and produced a new and useful Design 5 for a Coupling Member for Radiator-Valves; and I do hereby declare the following to be a full, clear, and exact description thereof.

My design relates to a coupling member for radiator-valves, the characteristic feature of which resides in the body, the same being flattened and broadened and extending sidewise and then rising, so as to form a circular side opening.

15 In the accompanying drawings, illustrating my design, Figure 1 is a perspective view of the coupling member. Fig. 2 is a side view, and Fig. 3 is a top view, of the same.

The coupling member is in the form of a 20 modified elbow having the opening 1, surrounded by the projecting cone 2, below which is the threaded face 3. The body of the coupling member is flattened and broadened, as indicated at 4, below and at one side of the threaded face 3, the body being low, as at 5, 25 and then rising at 6 to a height above the threaded face 3, forming a circular side opening which is surrounded by the angular faces 7. The form of the coupling member reduces the height of the valve and the flattened and 30 broadened portion thereof gives it a graceful and unique appearance.

What I claim is—

The design for a coupling member for radiator-valves herein shown and described. 35
In testimony whereof I, the said JOHN T. KELLY, have hereunto set my hand.

JNO. T. KELLY.
